US0D1093941S

(12) **United States Design Patent** (10) **Patent No.:** **US D1,093,941 S**
 (45) **Date of Patent:** **** Sep. 23, 2025**

(54) **STORAGE RACK FOR ELONGATED SPORTS EQUIPMENT**

(71) Applicant: **Robert Edgar Savadge**, Vero Beach, FL (US)

(72) Inventor: **Robert Edgar Savadge**, Vero Beach, FL (US)

(**) Term: **15 Years**

(21) Appl. No.: **29/992,572**

(22) Filed: **Mar. 10, 2025**

(51) LOC (15) Cl. **22-05**

(52) U.S. Cl.

USPC **D6/552**; D22/147

(57) **CLAIM**

The ornamental design for a storage rack for elongated sports equipment as shown and described.

DESCRIPTION

FIG. 1 is a front isometric view of a storage rack for elongated sports equipment showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof; and,

FIG. 8 is a rear isometric view thereof.

1 Claim, 8 Drawing Sheets
